UNITED STATES PATENT OFFICE.

JENS BERGH, OF DRAMMEN, NORWAY.

DEVICE FOR LOWERING OF LIFE-BOATS AND THE LIKE.

1,323,734.

Specification of Letters Patent.

Patented Dec. 2, 1919.

Application filed May 15, 1918. Serial No. 234,774.

To all whom it may concern:

Be it known that I, JENS BERGH, a subject of the King of Norway, residing at Drammen, Norway, have invented certain new and useful Improvements in and Relating to Devices for Lowering of Life-Boats and the like, of which the following is a specification.

This invention relates to devices for lowering and hoisting life boats and the like in connection with a ship so that when desired they may be lowered into the water or raised from the water and drawn inboard.

The object of the invention is a form of apparatus of this character in which, when the chocks or other devices for supporting the boat are removed, the boat is adapted, owing to its own weight, by means of the davits to be swung automatically outboard, and wherein the lowering and the regulation of the speed at which the boat is lowered is controlled entirely from the boat.

Another object of the invention is the provision of means for hoisting up the boat so that it can be replaced on board, for instance after a trial lowering or on any other occasion.

Reference will now be made to the accompanying drawings which illustrate one embodiment of an apparatus constructed according to the invention, and in which,

Figure 1 is a side view of one of the davits and the means for lowering the boat which is shown as being supported by the davit.

Fig. 2 is a view of the same device as seen from the right hand of Fig. 1.

Fig. 3 is a sectional view partly in elevation through the braking apparatus and the means that are used for releasing the boat from the wire or rope by means of which the boat is suspended from the davits.

Fig. 4 is an end view of Fig. 3, and

Fig. 5 is a sectional view on a line taken through the releasing apparatus when the parts are in gripping or engaged position.

In carrying the invention into effect the davits of which, as usual, two for each boat are employed, are each mounted in a frame 1, which in any suitable manner is secured to the deck with the davits pivoted on a journal or axle 2 in the upper end of each of the said frames. The davits are each formed as a double crank lever, the part 4 of which is slotted as at 5, in which the journal or axle 2 is guided or engaged. The outer part 6 of the crank lever is angular

and forms a shoulder 7 which is adapted, during the lowering of the boat to bear against the frame 1. The upper end of the part 6 is suitably for the purpose provided with rollers 8 and 9 or the like. The length of the different parts of the davit in combination with the arrangement of the said davit on the deck, are so selected that during lowering, the boat will pass clear of the side of the ship.

The device acts in the following manner:

When the boat is manned the chocks are removed, as usual, whereupon the weight of the boat will act on the davit through the wire or rope which will accordingly be unwound from the roller 12, the braking apparatus in the boat being in advance so adjusted as to give any suitable or desired speed for lowering. The davits at the same time will swing upon the journal or axle 2 until the shoulder 7 comes into contact with the frame 1, whereupon the journal 2 will serve as a guide to the moving part 4 of the davit, then moving relatively by means of its slot 5 to the journal 2 until the upper part of the davit has reached a normal horizontal position, as indicated in dotted lines. During these two movements of the davit, the roller 32, sliding ring 34, and the roller 31 are rotated and their method of operation is hereinafter described. The object of the two movements of the davit as above described is to insure that the boat in swinging outboard and being lowered will not contact with the side of the ship.

At each end of the boat the lowering device together with the davit are provided and these lowering devices principally consist in a roller system which is hereinafter described and are arranged upon a shaft 10, which in a known manner, by means of a clutch device or the like is connected with a driving device such as a motor or the like (not shown in the drawings), and the said motor which is to be used only for the hoisting of the boat is preferably placed between two boats, arranged end to end so that it can be connected to each of the shafts 10 of the respective lowering devices for each of the boats.

As before mentioned, the roller system is arranged upon a shaft 10 and this is supported by bearings 11, arranged upon the deck or at any other convenient part of the ship. The bearings are arranged preferably

two on each side of each roll system, and one in the middle between the roll systems. Each of these comprise the rollers 12 and 13 which are keyed upon the shaft 10, the 5 diameter of the said rollers being so arranged that the weight of the boat, owing to their difference in size will effect the desired action of lowering the boat. Around these rollers 12 and 13, there is wound a 10 wire the ends of which are attached to the rollers 12 and 13 respectively. The wire runs from the roller 12, over the roller 8 at the top of the davit, and from thence down to the roller 14 in the braking apparatus 15 which is mounted in one end of the boat. From the roller 14 the wire then passes back to the second roller 9 at the top of the davit and finally, to the second roller 13 to which the other end of the wire is attached.

20 When the boat is disconnected or unshipped so as to hang in the davits and upon the wire by means of its whole weight, the differential diameters of the rollers 12 and 13 will effect the lowering of the boat, the 25 larger roller 12 unwinding much more wire for each revolution than can be wound upon the smaller roller 13. During this operation the motor above referred to is disconnected since as before stated, this motor is only 30 used for hoisting the boat inboard.

The speed at which lowering occurs can be regulated from the boat by means of a braking apparatus, see Fig. 3, which comprises a grooved roller 14, around which 35 passes the wire or rope from the rollers 12 and 13. The latter is adapted to pass twice between metal blocks 15, 16 and 17 arranged a short distance above the roller 14 and a braking action is produced when the handle 18 is rotated by means of a screw 19 on a rod which is adapted to be actuated by the handle 18 and by which rotation, the pressure upon the wire passing between the metal blocks 15, 16 and 17 can be easily regulated.

45 In order to effect an easy release of the boat from the braking apparatus after it has reached the water the braking apparatus is fitted with a special releasing device 50 mounted on the boat. As is well known an ordinary hook is used for releasing the boat, but as it is difficult to obtain the necessary slack on the wire by which the boat is suspended, and as it is very important that the 55 boat shall be released just as quickly as possible, a modified arrangement has been designed for effecting this purpose and which will now be described. The releasing apparatus comprises two parts of which one part 60 as mentioned, is mounted on or attached to the boat and the other part is attached to and formed as one piece together with the braking apparatus. As is seen in Fig. 3 the part which is attached to the boat, consists 65 of an angular arm 20, one end of which in

a suitable manner is attached to the end of the boat, the other end 21 of the said arm being provided with the part 24, that can be rotated by means of a handle 22 and which is provided with a stop 23. The horizontal part 21 and the end of the upper arm 20 is designed to engage with a cylindrical opening in the other part of the releasing apparatus and the stop 23 engages with a hole 27 in the casing 28 which is placed in 70 the opening 26 so that it can be rotated. The casing is guided by two bolts 29. When the stop 23 is placed in the hole 27 and the handle 22 is rotated so that the hole 27 will be in its lowest position, the releasing device 75 will be locked and the handle 22 can be held in its position by any suitable means.

It will be understood that it is only necessary to use one of the braking devices in the boat as all of the rollers of the same 80 boat are mounted upon a common shaft.

When the boat is to be hoisted the shaft 10 is connected to the motor which is not herein shown. The boat is then hoisted in such a way that the wire which is attached 90 to the boat is wound around the larger roller 13 and at the same time unwound from the smaller roller 12. The hoisting in this manner takes place until the lower arm 6 of the davit is swung up. By means of a clutch 95 device 30 in this manner the roller 31, which slides on the shaft 10 and on which a wire 31' is running, is connected. One end of this wire 31' is attached to the said roller and its other end is passed through a purchase-block on the deck and attached at a suitable point, for instance, at the point 3 on the moving part of the davit. On the shaft 10 there is however provided a keyed roller 32 which is grooved circumferentially. 100 Between the rollers last mentioned a sliding ring 34 is provided, to a projection 35 on which there is attached one end of a wire 31'' which is hooked in the groove 33 and wound upon the roller 32. The other end of 105 this wire 31'' passes through a purchase-block and is attached at a suitable point, for instance, the point 3^a of a moving part of the davit.

When the clutch device 30 is brought or 110 moved into engaging position the slot 5 in the part 4 of the davit will slide on the journal 2 owing to the drawing power in the wire 31' attached at the point 3. The shoulder 7 will thereupon act as a center of rotation, and slack in the wire which is attached to the sliding ring is thereby obtained, whereupon this wire is hooked in the groove 33 in the ring 32, which roller at first cooperates with the hoisting and then effects 115 the last part of this movement alone. During the final swing of the davit by which the journal 2 serves as a center of rotation the sliding roller 31 must be disconnected so that it shall not prevent the movement. The boat 120

is now in its proper place inboard and the chocks can be placed underneath it as usual. The proper moment for the connecting in of the roller 31 can be marked, for instance by 5 an easily perceptible mark or device on the wire for the rollers 12 and 13.

During the lowering of the boat the roller 32 rotates together with the shaft whereby all the wire will be wound off the said roller. 10 Then the wire slips out of the groove 33 while the ring 34 continues sliding on the shaft and it is of no consequence whether the roller 31 is connected to the shaft or not. During this movement the 15 davit consequently is lowered to its lowest position, the shoulder 7 bearing against the davit frame.

What I claim is:

1. Apparatus for lowering and hoisting life-boats comprising in combination a pair of davits, each formed as a double armed lever one arm of which is slotted, a frame for supporting each davit, a journal or axle on the frame constituting a fulcrum for each 25 double armed lever, a projecting knee portion on the other arm of the double armed lever adapted to bear against the frame so that the davit may in its movement first swing upon its fulcrum as a center of rotation and afterward swing upon its projecting knee as a second center of rotation, a means for suspending the boat in the davits and means for lowering and hoisting the boat from the davits.

2. Apparatus for lowering and hoisting life boats comprising in combination a pair of davits each formed as a double armed lever one arm of which is slotted, a frame for supporting each davit, a journal or axle 30 on the frame constituting a fulcrum for each double armed lever, a projecting knee portion on the other arm of the double armed lever adapted to bear against the frame so that the davit may in its movement first swing upon its fulcrum as a center of rotation and afterward swing upon its projecting knee as a second center of rotation, wires for suspending a boat from the davits a large and a small roller on the ship to 35 which the respective ends of the wires are attached and means on the boat and on the davits over which the intermediate parts of the wires are passed, so that upon lowering the boat the wire is wound from the large 40 roller and wound upon the smaller roller.

3. Apparatus for lowering and hoisting life boats comprising in combination a pair of davits, each formed as a double armed lever one arm of which is slotted, a frame for supporting each davit, a journal or axle on the frame constituting a fulcrum for each 45 double armed lever, a projecting knee portion on the other arm of the double armed lever adapted to bear against the frame so that the davit may in its movement

first swing upon its fulcrum as a center of rotation and afterward swing upon its projecting knee as a second center of rotation, wires for suspending a boat from the davits a large and a small second roller on the ship 50 to which the respective ends of the wires are attached, means on the boat and on the davits over which the intermediate parts of the wires are passed so that upon lowering the boat the wire is wound from the larger 55 roller and wound upon the smaller roller, and a braking device on the boat for controlling the lowering of the boat and its speed.

4. Apparatus for lowering and hoisting 60 life boats comprising in combination a pair of davits each formed as a double armed lever one arm of which is slotted, a frame for supporting each davit, a journal or axle on the frame constituting a fulcrum for each 65 double armed lever, a projecting knee portion on the other arm of the double armed lever adapted to bear against the frame so that the davit may in its movement first swing upon its fulcrum as a center of rotation and afterward swing upon its projecting knee as a second center of rotation, wires for suspending a boat from the davits a large and a small second roller on the ship 70 to which the respective ends of the wires are attached, means on the boat and on the davits over which the intermediate parts of the wires are passed so that upon lowering the boat the wire is wound from the larger 75 roller and wound upon the smaller roller, and a braking device on the boat for controlling the lowering of the boat and its speed.

5. Apparatus for lowering and hoisting 80 life boats comprising in combination a pair of davits each formed as a double armed lever one arm of which is slotted, a frame for supporting each davit, a journal or axle on the frame constituting a fulcrum for each 85 double armed lever, a projecting knee portion on the other arm of the double armed lever adapted to bear against the frame so that the davit may in its movement first swing upon its fulcrum as a center of rotation and afterward swing upon its projecting knee as a second center of rotation, wires for suspending a boat from the davits a large and a small second roller on the ship 90 to which the respective ends of the wires are attached, means on the boat and on the davits over which the intermediate parts of the wires are passed so that upon lowering the boat the wire is wound from the larger 95 roller and wound upon the smaller roller, and means for readily releasing the boat from the suspending wires when lowered.

5. Apparatus for lowering and hoisting 100 life boats comprising in combination a pair of davits each formed as a double armed lever one arm of which is slotted, a frame for supporting each davit, a journal or axle on the frame constituting a fulcrum for each 105 double armed lever, a projecting knee portion on the other arm of the double armed lever adapted to bear against the frame so that the davit may in its movement first swing upon its fulcrum as a center of rotation and afterward swing upon its projecting knee as a second center of rotation, wires for 110 suspending both ends of the boat from the davits, a pair of large and small winding rollers on the ship to which the ends of the respective wires are fastened, a grooved roller detachably mounted at each end of 115 the boat to receive the intermediate portion of each wire, and means mounted in the boat at the ends thereof for exerting a braking pressure on the wires.

6. Apparatus for lowering and hoisting 120 life boats comprising in combination a pair of davits each formed as a double armed lever one arm of which is slotted, a frame for supporting each davit, a journal or axle on the frame constituting a fulcrum for each 125

double armed lever, a projecting knee portion on the other arm of the double armed lever adapted to bear against the frame so that the davit may in its movement first 5 swing upon its fulcrum as a center of rotation and afterward swing upon its projecting knee as a second center of rotation, wires for suspending a boat from the davits a large and a small second roller on the ship 10 to which the respective ends of the wires are attached, means on the boat and on the davits over which the intermediate parts of the wires are passed so that upon lowering the boat the wire is wound from the large 15 roller and wound upon the smaller roller, a braking device on the boat for controlling the lowering thereof and its speed and means for releasing the boat when lowered, the upper part of the releasing device being constructed in one with the said braking device. 20

7. Apparatus for the purpose described comprising in combination a pair of pivoted davits, wires on the davits attached to the boat, a pair of winding rollers on the ship 25 to which the respective ends of the wires are fastened, means whereby the boat is lowered by differentially winding and unwinding the wires, a power operated winding device, cables extending therefrom to one end of the pivoted davit and anchored at the other end, means whereby the power operated winding device raises the boat, which device may be clutched to the power drive when it is desired to cause the davits 30 to pivot on their fulcra for the purpose of drawing the boat inboard when it is raised sufficiently.

In testimony whereof I have signed my name to this specification.

JENS BERGH.
